UNITED STATES PATENT OFFICE

HELEN UFFORD, OF NEW YORK, N. Y., ASSIGNOR TO QUAKER OATS COMPANY, OF CHICAGO, ILLINOIS, A CORPORATION OF NEW JERSEY

DESIGN FOR A SUGAR BOWL OR SIMILAR ARTICLE

Application filed June 28, 1930. Serial No. 36,218. Term of patent 3½ years.

To all whom it may concern:

Be it known that I, HELEN UFFORD, a citizen of the United States, and resident of the borough of Manhattan, city, county, and State of New York, have invented a new, original, and ornamental Design for a Sugar Bowl or Similar Article, of which the following is a specification, reference being had to the accompanying drawing, forming part hereof in which Fig. 1 is a side elevation of a sugar bowl showing my new design, and Fig. 2 is a plan view thereof.

The side of the bowl opposite to that shown in Fig. 1 does not bear ornamentation such as illustrated in said figure, but is plain and conventional.

I claim:

The ornamental design for a sugar bowl or similar article, as shown and described.

HELEN UFFORD.
